UNITED STATES PATENT OFFICE.

WALTER T. GREENE, OF ROXBURY, BOSTON, MASSACHUSETTS, ASSIGNOR TO ENES J. NOKES, OF MEDFORD, MASSACHUSETTS, AND EDWARD F. NICOLAI, OF ROSLINDALE, MASSACHUSETTS, COMPOSING THE FIRM OF NOKES AND NICOLAI.

GAS SAVER FOR HYDROCARBON ENGINES.

Application filed October 14, 1921. Serial No. 507,780.

To all whom it may concern:

Be it known that I, WALTER T. GREENE, a citizen of the United States, residing at Roxbury, Boston, in the county of Suffolk and State of Massachusetts, have invented 5 certain new and useful Improvements in Gas Savers for Hydrocarbon Engines; and I do hereby declare the following to be a full, clear, and exact description of the invention, such as will enable others skilled in the art to which it appertains to make and use the same.

The present invention relates to an improvement in gas savers for hydro-carbon engines.

The object of the invention is to produce a gas saver for use in the intake passage of an automobile engine of cheap and efficient construction. To this end the invention 20 consists in the gas saver hereinafter described and particularly defined in the claim.

In the accompanying drawings illustrating the preferred form of the invention, Fig. 1 is a sectional elevation of a portion of a carburetor and intake manifold of an automobile engine provided with the gas saver forming the subject of this invention; and Fig. 2 is a front elevation of the gas saver shown separately.

30 The illustrated embodiment of the invention is described as follows:—The flange of the carburetor 1 is bolted to the flange of the intake manifold 2, and between these two flanges is placed a gasket 3, provided with a column of felt washers 4, supported on a wire 5, the ends of which are received between the two metallic surfaces of the gasket 3.

The column of felt washers 4 is arranged 40 vertically in the horizontal intake pipe, and any fuel condensing on the walls of the pipe beyond the gas saver flows down the pipe to the column of washers, where it is absorbed and lifted by the capillarity of the felt into position to be evaporated by the stream of fuel and air flowing through the pipe. Furthermore, any particles of fuel striking the column of felt washers will be arrested and gradually evaporated, as a result 45 of which the mixture of air and fuel

will be more intimate. In addition to this, the column of felt washers acts to cause turbulence in the gases and vapors passing it, so as thereby to secure a more intimate mixture of the air and the fuel. The felt washers, by reason of their rough surfaces, increase the disturbance of the air and fuel particles as they pass by them, because the column of washers acts with high skin frictional resistance to the passages of the air and fuel by it. The use of felt washers is 55 convenient because any suitable number of washers may be used corresponding to the diameter of the opening in the pipe passage in which the gas saver is located.

While it is preferred to place the column of washers in a vertical position because in such position it absorbs any fuel running down the pipe toward the carburetor and presents it to evaporation by the inflowing 60 body of air, still benefits are derived from the use of the column in a horizontal position, because of the rough surface which the column presents to the body of air and fuel passing it, which body of air and fuel is 65 thereby caused to be more intimately mixed, and the fuel to be more finely divided than otherwise.

The gas saver of the present invention is 70 preferably embodied in a gasket, as is shown in the drawings, in which form it constitutes a convenient article of commerce, the gasket constituting a support or frame for carrying the column of felt washers.

It has been found in actual use that the 75 gas saver of the present invention, when installed between the carburetor and manifold of a small car, effects an increase in mileage per gallon of fuel of from two to eight miles per gallon. This increase in mileage 80 per unit of fuel is due in part to the fact that this gas saver permits the reduction of the amount of fuel supplied with a given quantity of air. Thus, in such a car, the adjusting screw for regulating the richness of 85 the mixture may be screwed down a considerably greater distance when this saver is used, and this is believed to be due to the fact that the mixture is rendered much more uniform by its use, with the result that the 90

amount of fuel used per unit of air is decreased, and the efficiency of the motor is thereby increased.

Having thus described the invention, what is claimed is:

A gas saver for hydro-carbon engines, consisting of a gasket adapted to be clamped

between the surfaces of the connections of the intake passage, a wire extending on one side of the gasket to the other across the opening therein, and a plurality of absorbent washers loosely mounted on the wire.

WALTER T. GREENE.
